UNITED STATES PATENT OFFICE.

ACEPH B. MAYES, OF HOUSTON, TEXAS.

ELEVATOR.

1,065,544.

Specification of Letters Patent. Patented June 24, 1913.

Application filed November 27, 1911. Serial No. 662,662.

To all whom it may concern:

Be it known that I, ACEPH B. MAYES, a citizen of the United States, residing at Houston, in the county of Harris and State 5 of Texas, have invented certain new and useful Improvements in Elevators, of which the following is a specification.

My invention relates to new and useful improvements in elevators.

10 The object of the invention is to provide a device of the character described composed of tubular telescoping sections forming a complete unit within which fluid pressure may be introduced whereby the device 15 may be elevated or lowered correspondingly as the pressure is increased or diminished. The device is specially adapted to be used as a movable elevator which may readily be collapsed and will thus occupy small 20 space and may be easily moved from place to place.

With the above and other objects in view, the invention has particular relation to certain novel features of construction, operation 25 and arrangement of parts, an example of which is given in this specification and illustrated in the accompanying drawings, wherein—

Figure 1 is a side elevation, partially in 30 section, of the complete device. Fig. 2 is a side elevation of the device completely extended and showing guy wires for supporting the same secured thereto and such as would be used for a wireless station and like 35 purposes. Fig. 3 is a side elevation of a plurality of the elevators formed into a derrick. Fig. 4 is a plan view of a spider forming the top of said derrick and connecting the elevators together and Fig. 5 40 is a side elevation partially in section, of the base upon which each of the derrick elevators is mounted.

Referring now more particularly to the drawings wherein like numerals of reference 45 designate similar parts, in each of the figures, the numerals 1, 2 and 3 refer, respectively, to the base, intermediate and top sections of the elevator which telescope within each other in inverse order of the 50 numerals, the section 3 telescoping within the section 2 and the section 2 telescoping within the section 1 in the manner herein-after to be more explicitly set forth.

The bottom section is secured to a suitable base 4 which in turn may be secured to any suitable support for the elevator. The

lower ends of the sections 2 and 3 are enlarged so as to fit closely within the respective sections 1 and 2 and these enlarged ends are provided with a plurality of annular grooves 5 provided to receive suitable packing rings 6 which are provided to render the joints between said sections impervious to fluid passage. The upper ends of the sections 1 and 2 are provided with 60 annular inwardly extending shoulders 7 which, respectively, fit closely around the respective sections 2 and 3 and form bearings therefor and engage, respectively, against the enlarged lower ends of sections 2 and 3 and prevent the sections from complete disengagement from each other, and the upper ends of sections 1 and 2 are outwardly threaded and receive the respective nuts 8 and 9 between which the annular 65 rings or flanges 10 are secured. These flanges are provided with marginal perforations 11 around the edges thereof through which the guy wires 12, for supporting the elevator, may be passed in order that they 70 may be secured to said flanges. A similar flange 13 is secured at the top of the section 3 between the nuts 14 and 15 for a similar purpose to that of the flanges 10. The upper end of the tubular section 3 is 75 closed by means of a plug 16 so as to prevent the escape of fluid pressure there-through. The lower end of the section is also inclosed by means of a cap 17 which is secured there over and a completely inclosed chamber is thus provided within the 80 telescoping sections.

Fluid pressure, either air, steam or hydraulic, may be introduced from any suitable compressor through the orifice 18 and the 85 telescoping sections thereby fully extended. It is obvious that the amount of extension can easily be regulated in accordance with the amount of pressure produced.

Interposed between the enlarged lower 90 end of section 3 and shoulder 7 of section 2 is a strong coil spring 25 which surrounds the section 2 and is provided to break the shock in case of sudden extension.

This device may be used as a collapsible 95 stem for a wireless station as shown in Fig. 2 or it may be used as an elevator and when used for the latter purpose is specially adapted for the purpose of rescuing persons from tall buildings or to elevate firemen to 100 upper stories in cases of fire and will be found specially useful for this purpose in-

asmuch as it can be readily collapsed and quickly transported to the place where the rescue is to be effected or the flames are to be extinguished.

- 5 It is sometimes desirable to use a plurality of these elevators in conjunction in the form of a derrick, in which case they should each be mounted upon a universal bearing, shown in Fig. 5 and have their 10 upper ends connected to a spider 19, shown in detail in Fig. 4. These bearings include a base 20 having a socket therein. The socket is provided to receive a hollow ball shaped casting 21 having a ground outer 15 surface. This ball is provided with a threaded neck 22 upon which the lower end of section 1 is screwed. At the bottom of the socket is a chamber with which the fluid compressor communicates and which in turn 20 communicates with the interior of the ball 21. The fluid compressor communicates with the socket chamber either through the passageway 23 in the side of base 20 or through the bottom thereof through orifice 25. It is to be understood that when either the passageway 23 or orifice 24 is used for the admission of fluid pressure the other of said passageways should be closed.
- It is further to be observed that when the 30 elevators are used separately and not in the form of a derrick, as shown in Fig. 3, they

may be hingedly mounted upon their base, as shown in Fig. 5 and not upon the rigid base shown in Fig. 1.

What I claim is:—

1. A device of the character described composed of a plurality of elevators each being composed of tubular telescoping sections, a base for each elevator upon which said elevator is hingedly mounted, a spider 40 hingedly securing together the upper ends of said elevators, each of said elevators being provided with an orifice for the admission of fluid pressure therein.

2. A device of the character described 45 composed of a plurality of elevators, each being composed of tubular telescoping sections, a base for each elevator upon which the same is hingedly mounted, a spider having radiating arms which are hingedly secured to the upper ends of the respective elevators and which secure said upper ends together, each of said elevators being provided with an orifice for the admission of fluid pressure therein.

In testimony whereof I have signed my name to this specification in the presence of two subscribing witnesses.

ACEPH B. MAYES.
